(57) CLAIM

The ornamental design for a bottle case, as shown and described.

DESCRIPTION

FIG. 1 is a front elevational view of a bottle case showing my new design;

FIG. 2 is a top and front perspective view thereof;

FIG. 3 is an exploded top and front perspective view thereof;

FIG. 4 is a left side elevational view thereof, the right side elevational view being a mirror image thereof;

FIG. 5 is a rear elevational view thereof;

FIG. 6 is a top plan view thereof;

FIG. 7 is a bottom plan view thereof;

FIG. 8 is a front elevational view of a second embodiment of bottle case; and,

FIG. 9 is an exploded top and front perspective view of FIG. 8.

The “Heavy Water” trademark forming part of the claimed design is a pending trademark of The Heavy Water Company.

The “D₂O” trademark forming part of the claimed design is a pending trademark of The Heavy Water Company.1 Claim, 6 Drawing Sheets*FIG. 2
